UNITED STATES PATENT OFFICE.

JOB SMITH, OF PHILADELPHIA, PENNSYLVANIA, ASSIGNOR TO GEORGE C. HETZEL & CO., OF SAME PLACE.

APPARATUS FOR DYEING.

SPECIFICATION forming part of Letters Patent No. 406,784, dated July 9, 1889.

Application filed April 29, 1889. Serial No. 308,950. (No model.)

To all whom it may concern:

Be it known that I, JOB SMITH, a citizen of the United States, and a resident of Philadelphia, Pennsylvania, have invented certain 5 Improvements in Dyeing-Machines, of which the following is a specification.

My invention relates to that class of machines used for dyeing, washing, or scouring yarn, in which the skeins of yarn are carried 10 through the liquid upon suitable frames; and it consists of certain improvements in the construction and operation of such a machine, as more fully described hereinafter.

It has been proposed to construct a dyeing-15 machine in which the skeins are mounted upon frames secured to a rotating reel which carries the yarn into and out of the dyeing-liquid; but such machines, even when built of the largest practical dimensions, have but 20 a limited capacity, and where a large quantity of yarn is to be dyed of the same color or shade it is objectionable to dye such small quantities at a time, for the reason that it is almost impossible to obtain exactly the same 25 shade in different batches, whereas the construction I propose to employ is capable of dyeing at a single operation any desired quantity of yarn, so that a uniformity of color or shade is secured, which could not be obtained were the yarn treated in small batches 30 at different times.

It has also been proposed to secure the skeins of yarn lengthwise upon endless belts, and to guide such endless belts into and out 35 of the dyeing-liquid by suitable rollers; but, in addition to the limited capacity of the machine so constructed, it is objectionable to carry the skeins or hanks of yarn repeatedly over guiding-rolls, as the yarn is subjected to 40 more or less injurious pressure at each such contact.

In the accompanying drawings, Figure 1 is a longitudinal sectional elevation on the line 1 2, Fig. 2, of a dyeing-machine constructed 45 in accordance with my invention. Fig. 2 is a transverse sectional elevation of the same on the line 3 4, Fig. 1; and Fig. 3 is a detached perspective view of a portion of the yarn-car- 50

rying device.

To suitable bearings in the sides of a vat

or tank X are adapted shafts x, provided with sprocket-wheels B B, carrying endless chains A A, which preferably extend as close to the ends of the vat or tank as is permitted by the character of the yarn-carrying frames, 55 the endless chains being close to the opposite sides of the tank.

To the chains A are secured at suitable intervals transverse bars a, and to the latter are secured opposite upright bars or posts a', 60 to which are affixed suitable retainers d e, for the reception of transverse bars d' e', on which the skeins or hanks of yarn to be dyed are mounted.

It will be noticed that the retainers d have 65 formed in them a series of orifices, to any one of which the lower bar d' may be adapted, according to the length of the skein or hank of yarn to be treated. The shaft of one of the sprocket-wheels is provided with suitable 70 driving mechanism by which the chains and yarn-holding frames carried thereby may be moved.

The action of the machine is as follows: The skeins or hanks of yarn are first strung 75 upon the bars d' e', each of the bars a' being provided near each end with a guard or shield f, to prevent the skeins or hanks from working out against the inner sides of the bars a', where the dyeing or scouring liquid cannot 80 gain access to them. The bars e' are then placed in the retainers e, and the bars d' are adapted to such of the orifices of the retainers d as the lengths of skein or hank render most available. After all of the series of 85 frames have been loaded with yarn in this manner motion is imparted to the endless chains; hence the yarn-carrying frames will be caused to traverse with the chains in the direction of the arrow, and the yarn will be 90 immersed in the liquid at one end of the vat or tank, will be carried through said liquid to the opposite end of the tank, and then lifted from the liquid and returned to the starting-point, the repeated carryings of the yarn 95 through the liquid causing the access of the latter to all portions of the skeins or hanks during their travel through the tank, so as to effect the thorough scouring or dyeing of the yarn.

I claim as my invention—

1. In a machine for dyeing or scouring yarn, the combination of a vat or tank, an endless chain traversing said tank, and a series of yarn-holding frames mounted upon said endless chain, said frames consisting of bars projecting outward from the chain and having lateral yarn-carrying arms, substantially as specified.
- 10 2. In a machine for dyeing or scouring yarn, the combination of the vat or tank and endless chains traversing said tank with a series of yarn-holding frames mounted upon said endless chains, each frame consisting of a cross-bar extending from chain to chain, upright bars extending from said cross-bar, and transverse yarn-carrying rods supported upon said upright bars, substantially as specified.
- 15 3. In a machine for dyeing or scouring

yarn, the combination of a vat or tank and an endless chain traversing said tank with a series of frames secured to said chain, each of said frames having a series of orifices for the reception of the yarn-carrying bars, substantially as specified. 25

4. In a machine for dyeing or scouring yarn, the combination of a vat or tank and an endless chain traversing said tank with a series of yarn-supporting frames carried by 30 said chain, each frame having guards to retain the hanks of yarn in proper lateral position, as set forth.

In testimony whereof I have signed my name to this specification in the presence of two 35 subscribing witnesses.

JOB SMITH.
